REUBEN AUGUSTUS OAKLEY, OF MONTREAL, QUEBEC, CANADA,
ASSIGNOR OF ONE-HALF TO VICTOR GUERTIN, OF MONTREAL,
CANADA.

LOOSE-LEAF LEDGER AND BINDER.

No. 835,196.

Specification of Letters Patent.

Patented Nov. 6, 1906.

Application filed May 31, 1904. Serial No. 210,523.

To all whom it may concern:

Be it known that I, REUBEN AUGUSTUS OAKLEY, of the city of Montreal, Province of Quebec, Canada, have invented certain new and useful Improvements in Loose-Leaf Ledgers and Binders; and I do hereby declare that the following is a full, clear, and exact description of the same.

This invention relates particularly to loose-leaf ledgers of the type having telescopic binding-posts; and it has for its object to provide a ledger adapted to clasp the removable leaves more tightly and to be more easily and uniformly manipulated and more durable than loose-leaf ledgers of this type heretofore used.

The invention may be said briefly to consist of a rotary locking device, in combination with non-rotatory part adapted to coact therewith and automatically lock the retaining-bars against displacement away from one another in any position to which they may be moved to clamp the leaves between them.

Another feature of the invention is means whereby the locking device is held or after having been moved or released by a key retained in such position until the key is withdrawn; and the invention further consists of means for distributing the pressure uniformly throughout the retaining-bars at whatever point along said bars it may be applied.

For full comprehension, however, of my invention reference must be had to the accompanying drawings, forming a part of this specification, in which similar reference characters indicate the same parts, and wherein—

Figure 1 is a top view of my improved loose-leaf-ledger binder. Fig. 2 is a similar view with the top plate removed and illustrating particularly the means for locking the clamping-bars of the device in any position to which they may be moved. Fig. 3 is a face view of my improved binder, and Fig. 4 is a longitudinal sectional view of the central binding-post of my improved binding means. Fig. 5 is an enlarged transverse vertical sectional view.

A pair of clamping-bars $b b'$ have a pair of metal plates $c c$, adapted to overlap one another, secured rigidly thereto. These plates

are preferably bent to present top and bottom c' and c^2 , respectively, back c , and ends c^3 .

A pair of telescopic tubes d and e , respectively, are secured rigidly to the clamping-bars midway of the length of the latter, and two other pairs f and g and h and i , respectively, are secured rigidly to the clamping-bars, and each of the pairs, as well as the first-mentioned pair, constitute a telescopic binding-post.

A worm k is located in the central telescopic post and is rotatably carried by the clamping-bar b , and a pair of lugs m , mounted rigidly upon the inside of the tube e , engage in the thread of this worm and cause the same to rotate when the clamping-bar carrying the said worm is moved toward and from the other clamping-bar. A gear-wheel n is mounted rigidly upon the outer end of this worm, which extends through the clamping-bar b , carrying the same, and said gear intermeshes with a second gear o , mounted rigidly upon a stub-spindle o' , carried by the clamping-bar b , while distance-pieces p establish the space between this clamping-bar b and the inclosing plate c to accommodate the gears n and o . A ratchet-wheel q is mounted rigidly upon the upper end of spindle o' , and the teeth thereof are adapted to be engaged by a pawl r , pivoted upon the upper end of the worm, upon which is also pivoted a lever s of substantially bell-crank form, and one arm whereof is provided with a laterally-projecting lug s' , adapted when the lever is moved in one direction to engage the pawl and move it out of engagement with the teeth of the ratchet-wheel, while the end of such arm is notched, as at s^2 , to fit upon and be stopped by a stop t when the lever is moved in the opposite direction, which movement releases the pawl and allows it to be thrown by a bow-spring u into engagement with the teeth of the ratchet-wheel.

The clamping-bars $b b'$ are caused to constantly lie parallel to one another whatever their distance may be away from one another and a pressure if exerted upon one end is distributed throughout same by a pair of toggle-bars 2 , pivotally connected together, as at 3 , and the ends of the said bars at one end of the device are pivotally connected to a pair of lugs 4 , carried rigidly by the clamp-

ing-bars, while their opposite ends are connected slidably to a pair of rigid lugs carried upon the opposite ends of the clamping-bars and slotted, as at 6, to receive a pair of studs 5 7, carried rigidly by the said opposite ends of the toggle-bars to effect a sliding connection therebetween and the said lugs.

Operation: The key is first inserted through a keyhole 8 in the cover 9 and into a recess 10 or aperture 10 of segmental form in the lever 5 and upon being turned in a direction toward the ratchet-wheel will displace the pawl from the latter and allow the worm freedom to rotate in a direction to allow the clamping-bars to move away from one another under the influence of a pair of expansile helical springs 11, located in the telescopic binding-posts *f,g* and *h,i*. The leaves are then placed upon the binding-posts and the key turned in 15 the opposite direction, thereby again causing the pawl to engage the teeth of the ratchet-wheel and preventing the same and the worm rotating in the direction to allow the clamping-bars to move away from one another, but at the same time allowing the said clamping-bars to be pressed toward one another, which is then done until the leaves put in place are clamped tightly, in which manner they are held until the key is again manipulated. The key is not required after the pawl is made to engage the ratchet-wheel and after this is done may be removed:

What I claim is as follows:

1. A binder for a loose-leaf ledger, consisting of a pair of clamping-bars, a tube and a rotatable worm carried by one of said bars the worm being in the axis of the tube, a tube carried rigidly by the other bar and adapted to be inserted into the first-mentioned tube 40 and receive the worm therein, a pair of pins carried rigidly by opposite sides of the interior of the last-mentioned tube and adapted to engage the thread of such worm and cause the rotation thereof in one direction or 45 the other accordingly as the bars are moved toward or from one another, the said worm being otherwise free of the interior of the tube in which it is located, locking means carried partially by the bar which carries the 50 worm and partially by the worm and adapted to retain the worm against rotation in one direction or allow the same freedom to rotate in both directions, for the purpose set forth.

2. A binder for a loose-leaf ledger, consisting of a pair of clamping-bars, means for limiting the movement of said bars away from one another and for guiding the same in their movement, of a worm carried rotatably by one of said bars, means secured to the 55 other bar and having a lug thereon adapted to engage the thread of said worm and rotate the latter in either direction according to whether the bars are being moved toward or from one another, a gear-wheel mounted

rigidly upon said worm in close proximity to 65 the clamping-bar carrying the latter, a second gear-wheel intermeshing with the first-mentioned gear-wheel, a spindle rotatably supported by said last-mentioned clamping-bar and having the second-mentioned gear-wheel mounted rigidly upon one end thereof, a ratchet-wheel mounted rigidly upon the opposite end of said spindle, a spring-pawl pivoted upon the worm and engaging the teeth of said ratchet-wheel, a lever fulcrumed upon the worm and adapted when moved in one direction to shift the said pawl out of engagement with the teeth of the ratchet-wheel and when moved in the opposite direction to allow of such engagement, 80 substantially as described and for the purpose set forth.

3. A binder for a loose-leaf ledger, consisting of a pair of clamping-bars, means for limiting the movement of said bars, away 85 from one another and for guiding the same in their movement, of a worm carried rotatably by one of said bars, means secured to the other bar and having a lug thereon adapted to engage the thread of said worm 90 and rotate the latter in either direction according to whether the bars are being moved toward or from one another, a gear-wheel mounted rigidly upon said worm in close proximity to the clamping-bar carrying the 95 latter a second gear-wheel intermeshing with the first-mentioned gear-wheel, a spindle rotatably supported by said last-mentioned clamping-bar and having the second-mentioned gear-wheel mounted rigidly upon one end thereof, a ratchet-wheel mounted rigidly upon the opposite end of said spindle, a spring-pawl pivoted upon the worm and engaging the teeth of said ratchet-wheel, a lever fulcrumed upon the worm and adapted 100 when moved in one direction to shift the said pawl out of engagement with the teeth of the ratchet-wheel and when moved in the opposite direction to allow of such engagement, said lever being adapted to be moved 105 by a removable key, substantially as described and for the purpose set forth.

4. A binder for a loose-leaf ledger, consisting of a pair of clamping-bars, a tube and a rotatable worm carried by one of said bars, the worm being in the axis of the tube, a tube carried rigidly by the other bar and adapted to be inserted into the first-mentioned tube and receive the worm therein, a pair of pins carried rigidly by opposite sides of the interior of the last-mentioned tube and adapted to engage the thread of such worm and cause the rotation thereof in one direction or the other accordingly as the bars are moved toward or from one another the said 115 worm being otherwise free of the interior of the tube in which it is located, locking means carried partially by the bar which carries the 120 worm and partially by the worm and adapted to retain the worm against rotation in one direction or allow the same freedom to rotate in both directions, for the purpose set forth.

worm and partially by the worm and adapted to retain the worm against rotation in one direction or allow the same freedom to rotate in both directions, a toggle-bar device, means 5 pivotally connecting one pair of corresponding ends of the toggle-bars to the ends of the clamping-bars at one end of the binder such pivotal connection preventing slidable movement of the said ends of the toggle-bars relatively to the clamping-bars, and means slidably and pivotally connecting the opposite ends of the toggle-bars to the ends of the clamping-bars at the opposite end of the binder, for the purpose set forth.

15 5. In a loose-leaf-ledger binder the combination with a pair of clamping members,

of a worm carried by one of such members, a device carried by the other member adjacent to the worm and adapted to engage the thread of the worm, a ratchet-wheel mounted 20 rotatably upon the member carrying the worm, a pawl, means retaining such pawl yieldingly in engagement with the teeth of such ratchet-wheel, and a train of gears operatively connecting the worm to the 25 ratchet-wheel.

In testimony whereof I have affixed my signature in presence of two witnesses.
